UNITED STATES PATENT OFFICE

HERBERT FRANK, OF CASSEL-WILHELMSHOHE, GERMANY, ASSIGNOR TO THE SUPER-HEATER COMPANY, OF NEW YORK, N. Y.

SUPERHEATER HEADER

Application filed January 10, 1931, Serial No. 507,850, and in Germany February 8, 1930.

The invention relates to divided superheater headers with finger-like subsidiary headers for the connection of superheater elements. Its purpose is to connect the superheater header and saturated header in such a manner that temperature stresses caused by differential expansion of the two chambers are avoided and that the changes in the relative location of the subsidiary headers caused by the longitudinal expansion of the headers be kept as small as possible. For this purpose the invention consists in having the two headers held firmly in their relative position only for a short distance by the connection provided on one of the long sides, for example, the back side, and that, except for this connection, a relative displacement of the headers in a longitudinal direction is possible whereas the connection of the other longitudinal side, for example the front side, permits of relative longitudinal and transverse displacement. According to an advantageous form of the invention, the two headers are equipped on their back sides with transversely arranged eyelets through which a rod extends, the rod carrying a distance piece between two neighboring eyelets of the saturated and superheated headers. In this manner the two headers are held firmly at their middle in their relative position, while they can move relatively to each other in the longitudinal direction of the rod. On the front side the two headers are connected, for example by means of vertically extending screws which have sufficient play in the openings of the connecting lugs of the superheated header in a known way, so that a displacement of the superheated header relative to the saturated header in the longitudinal direction and in the transverse direction is possible. The new connecting means therefore vouchsafe entire freedom of expansion of the superheater header due to heating so that dangerous stresses cannot occur. In order to preclude movement in a vertical direction and thus to avoid relative displacement of the subsidiary headers, it is advisable to provide for connection of the two headers on their front side by means of a continuous longitudinal bar against which the connecting lugs

of the two headers abut in such a manner that a relative movement of the subsidiary headers can occur only in a horizontal direction.

In the drawings, illustrative examples of the inventive idea are shown. Fig. 1 shows a rear view of one form of the invention, that is, a view from the smoke-box tube sheet of the locomotive. Fig. 2 is a view from below, and Fig. 3 a transverse section on line 3—3 of Fig. 2 on an enlarged scale. Figs. 4 to 6 show a header of another form also in rear elevation, in projection from below, and in cross-section, respectively, the last of these views being on line 6—6 of Fig. 5. Fig. 7 shows the same superheater header with another form of the invention, the view being from below.

In Figs. 1 to 3 the reference numeral 1 designates the saturated steam header with the longitudinal chamber 2, the transverse finger-like cross-headers 3 extending from this chamber, and the connection 4 to which the pipe carrying saturated steam from the boiler is connected. 5 is the superheated steam header with the longitudinal chamber 6, the finger-like transverse subsidiary headers 7 extending from it, and the connecting flanges 8 to which are attached the steam pipes leading to the steam chests. The saturated subsidiary headers 3 and the superheated subsidiary headers 7 are in the assembled header mutually intermeshed and separated from each other by the air spaces 9. Through these spaces extend the bolts (not shown) which serve to secure the superheater elements (also not shown) which communicate with the openings 10 in the bottom of the subsidiary headers. The saturated header is equipped laterally with lugs 12 by means of which it is supported in a known manner on brackets secured to the wall of the smokebox. At the rear side of the header the saturated header and the superheated header are connected by means of a round rod or bar 13 which extends through the eyelets 14 and 15 cast integral with the subsidiary headers 3 and 7. Between the middle eyelet 14 of the saturated headers and the two neighboring eyelets 15 of the superheated header, the rod 13 carries the disks 16, one on each side, which lie in close contact with the

lateral surfaces of the eyelets. In this way the relative spacing of the subsidiary headers 3 and 7 is fixed in the middle while at all other points the superheated header can elongate on both sides in the longitudinal direction of the axis of the connecting rod 13. On the front side the saturated header and the superheated header are connected by means of vertically extending bolts 18 which extend through openings in vertically aligned lugs 19 of the saturated header and 20 of the superheated header. In the openings 21 of the lugs 20, the bolts 18 have enough play to permit the superheated header to move freely both in a longitudinal and in a transverse direction. In order that this movement shall not be made difficult, the nuts 22 on the studs 18 are not pulled up tight.

In the case of the header shown in Figs. 4 to 6, the subsidiary headers do not extend toward each other as in the form first described but extend from the longitudinal channel 23 of the saturated header 24 and the longitudinal channel 25 of the superheated header 26 forward in the same direction. The subsidiary headers of the saturated header are designated by the numeral 27 and the intervening superheated subsidiary headers by the numeral 28. The connection of the saturated header and the superheated header on their back sides is accomplished in exactly the same way as in the case first described, that is, by means of a round rod which extends through eyelets 30 of the saturated header 24 and through eyelets 31 of the superheated header 36. Between the middle eyelet 30 and the two neighboring eyelets 31, the rod 13 carries the distance disks 16. On the front side, however, the lugs of the subsidiary headers are not connected in pairs by screws but rather a continuous bar 32 is used for this connection which engages recesses of the alternating lugs 33 of the saturated subsidiary headers 27 and 34 of the superheated subsidiary headers 28. The bar 32 is pulled up firmly against the bottom of the recesses in the lugs 33 by means of studs 35 which extend through the slotted holes of the bar 32. The recesses in the lugs 34 are deeper so that between the bar and the bottom of the recesses clearances 36 are left which make it possible for the superheated subsidiary headers 28 to expand freely in their longitudinal direction. In addition, the connection by means of the bar 32 permits a relative displacement of the subsidiary headers in their transverse direction, whereas the bar is fitted vertically in the recesses of the lugs 33, 34 in such a manner that a vertical relative displacement of the subsidiary headers is made impossible.

In the form of the invention according to Fig. 7, the connection of the saturated subsidiary headers 27 and the superheated subsidiary headers 28 on the front side is carried out in the way just described by means of a

continuous bar 32. On the back of the header, however, the superheated header and the saturated header are connected not through a continuous rod but there is provided at each end only a relatively short connecting bolt 38 which is inserted through the adjacent transversely arranged eyelets 39 of the saturated header and 40 of the superheated header. In the eyelet 39, the bolt 38 is freely movable whereas it is tight in the eyelet 40, nut 41 pulling the conical surface 42 of the bolt against a correspondingly shaped seat in the opening of the eyelet 40. In the middle of the header the saturated header 44 and superheated header each have two longitudinally arranged eyelets 43 and 44 connected rigidly to each other by means of the bolts 45. It will be seen that in this form of the connection the saturated header and superheated header are therefore held firmly in their relative position only on their rear side and only over a short distance near the center so that the expansions of the superheated header due to heat can occur without hindrance.

I claim:

1. A two-part superheater header, the two parts each having subsidiary transverse headers, those of one part alternating with those of the other, said parts being secured together, characterized by the fact that the two parts are held firmly in their relative position only at one side and over only a short distance near the center whereas they are held relatively to each other at other points of the said side and at the opposite side in such a way that relative longitudinal and transverse displacements are possible.

2. A superheater header comprising two separate parts each having subsidiary transverse headers, those of one part alternating with those of the other, and means to secure the two parts together, said means comprising transverse eyelets on one side of the headers and distributed along the entire side, a bar passing through the eyelets, and a distance piece on the bar adjacent to and contacting with two neighboring eyelets.

3. A superheater header in accordance with claim 2, the two parts being further connected at their sides opposite the side having the eyelets by bolts extending vertically through holes in the parts, the holes of one part being larger than the bolts to permit relatively horizontal movement between the two parts.

HERBERT FRANK.
